Primary Examiner—Paula A. Mortimer*Attorney, Agent, or Firm*—Ryan Kromholz & Manion, S.C.[57] **CLAIM**

The ornamental design of a trim for a bill of a cap, as shown and described.

DESCRIPTION

FIG. 1 is a perspective view of a trim for a bill of a cap showing my new design; the broken lines showing of the cap is for illustrative purposes only and forms no part of the claimed design;

FIG. 2 is a perspective view of the trim for a bill of a cap; FIG. 3 is a right side elevational view of the trim for a bill of a cap, the left side elevational view being identical to the right side elevational view;

FIG. 4 is a top plan view of the trim for a bill of a cap; and,

FIG. 5 is a bottom plan view of the trim for a bill of a cap.
